UNITED STATES PATENT OFFICE.

LELAND L. SUMMERS, OF CHICAGO, ILLINOIS, ASSIGNOR TO CONTINUOUS PROCESS CORE COMPANY, OF CHICAGO, ILLINOIS, A CORPORATION OF MAINE.

COOKING-OVEN.

992,078.

Specification of Letters Patent. Patented May 9, 1911.

Application filed February 11, 1908. Serial No. 415,378.

To all whom it may concern:

Be it known that I, LELAND L. SUMMERS, a citizen of the United States, residing at Chicago, in the county of Cook and State 5 of Illinois, have invented certain new and useful Improvements in Coking-Ovens, of which the following is a specification.

The object of my invention is to provide an improved coking oven, and, among other 10 features of construction and operation, to provide means for vertically transmitting heat to coal contained in a closed retort, thereby securing coke of a compact formation. In order to accomplish this result I 15 construct the top of the retort in the form of a hollow arch, making the retort preferably of considerably greater width than height, and so regulating its height that heat may readily be transmitted to all parts 20 of the interior by vertical transmission from flues above and below.

My invention further relates to means whereby the coal may be continuously fed and the coke continuously discharged from 25 the retort and whereby the greatest heat is applied to the retort at the discharge end, the heat progressively decreasing toward the receiving end, thus avoiding the possibility of chilling the most highly heated 30 part of the retort by fresh coal.

As is well-known the escape of the volatile products from coal, which escape takes place in a vertical direction gives rise to fissures in the body of the coke, such fissures 35 resulting in causing the coke to form in fingers. This is especially the case when the coal is distilled in retorts of a type which is old in the art. In the ordinary vertical oven the retorts are comparatively narrow, 40 having a width of from ten to twenty inches with a height of from five to seven feet and a length of from twenty to thirty feet. In such retorts the heat is applied at the sides, as distinguished from the top and bottom 45 as in my improved furnace, and the comparatively great height of the vertical retorts renders it necessary for the liberated products of distillation to pass through a large body of the material being coked before they finally escape at the top of the furnace. This gives rise to vertical fissures 50 in the coke, and the coke is further disintegrated by horizontal fissures because of the horizontal transmission of heat, it being 55 found in practice that the coke will disinte-

grate along lines lying in the direction of heat transmission. In the vertical ovens the heat is transmitted at a right angle to the line of escape of the products of distillation, thus giving rise to two sets of fissures, and breaking the coke up to an undesirable extent.

It is one of the objects of my invention to transmit the heat to the material in a closed retort in a vertical direction, thus causing 65 the heat transmission to lie in the same direction as the line of escape of the gaseous products. I accomplish this object by the means hereinafter described and thus avoid the principal source of disintegration of 70 coke in vertical furnaces, which cause consists in the transmission of heat in a direction different from the line of escape of the products of distillation.

My invention further includes means for 75 heating the air used to support combustion in the heating furnace, such means including a system or systems of flues leading from the less highly heated receiving end to the more highly heated discharge end. The air flues 80 preferably lie outside of and adjacent the heating flues.

Further improvements consist in the form of construction of my oven whereby the heating or combustion flues, which are more 85 subject than other parts of the oven to deterioration, are supported independently of the main structure portion of the oven and in such manner as to be readily renewed.

Another feature of my invention consists 90 in means for quenching the coke by discharging the same into a pool of water, the pool of water, or quenching basin, communicating with the retort and being sealed against the outside atmosphere by a water seal, whereby the steam formed in the process of quenching the coke is confined within the retort, and thus, by contact with the hot coke, water gas is formed.

My invention also has for its object the 100 provision of means for separating the different by-products by drawing off the gases from different parts of the retort, such parts having different temperatures by reason of the system of heating employed.

In the drawings—Figure 1 is an elevation partly in section of a coking oven constructed according to my invention. Fig. 2 is a plan view partly in section of the oven shown in Fig. 1. Fig. 3 is a transverse sec- 110

tion of the oven on the line 3 of Fig. 1. Fig. 4 is a transverse section on the line 4 of Fig. 1. Fig. 5 is an end view of the discharge end of the oven partly in section. Fig. 6 is an end view of the receiving end of the oven. Fig. 7 is a fragmentary side elevation partly in section of the discharge end of the oven. Fig. 8 is a fragmentary sectional view on the line 8 of Fig. 3.

The outer part of my improved furnace consists of side walls 40 supporting the arch 41, said arch and side walls inclosing the operative parts of the retort and restraining radiation of heat therefrom. The retort proper consists of a central chamber 42 extending from the receiving end 43 to the discharge end 44. In the present instance I have illustrated a double retort having two chambers side by side, but it may be found preferable in some instances to use a greater number or a single chamber.

The upper wall of the retort at the discharge end consists of an arch or arches formed of hollow tiles 45. Similar hollow tiles 45 form the lower wall of the retort at the discharge end. Said hollow tiles form passages 12 through which the burned and burning gases pass in the manner hereinafter described. Resting immediately upon the floor 46 of the furnace are conduits 47 upon which the tiles 45, above referred to, are supported. The conduits 47 may be constructed of any suitable material. Resting upon the top of the arch tiles 45 are conduits 13. The tile arches 45 are supported upon walls 46 which rest upon the upper surface of the lower tiles 45. The side walls 40 are lined with firebrick 48 or other suitable material and are formed at their upper ends 40 to take the thrust of the upper arches 45. The tiles 45 are used at the discharge end of the furnace, and extend about half way toward the receiving end, this part of the furnace being subject to the highest temperature. At the receiving end of the furnace the tiles 45 may be replaced by the cast iron construction 49 shewn at the right in Fig. 1 and in Fig. 3. Conduits 12 above and below the retort communicate with each other through vertical passages 50. The walls between the vertical passages 50 are provided with apertures 25, as shown in Fig. 4. At intervals, however, continuous vertical walls 11 Fig. 2, are provided.

The necessary heat is supplied by a gas burner, designated generally by the numeral 60. The products of combustion are discharged into the vertical passages opposite the burner and pass partly above and partly below the retort to the opposite side where they move longitudinally through the openings 25 until they meet the next continuous wall, whereupon, they move back across the furnace through the conduits 12 above and below and so on back and forth until they

reach the discharge end of the furnace where they are conducted through a suitable outlet 51 to a chimney or are utilized for any desired purpose. The conduits 13 above and below the conduits 12 are utilized for the purpose of heating the air used to support the combustion of gases in the burner 60. Air for this purpose is admitted through the pipe 10 to both the upper and lower sets of flues 13 and circulates back and forth through said flues, as indicated by the arrows Fig. 8, finally reaching the discharge pipe 14 in a highly heated condition, and is then conducted to the burner 60. For the purpose of feeding coal to the furnace I provide a hopper 16 at the receiving end in conjunction with a ram 17. The ram 17 is actuated by a hydraulic, steam or air cylinder 18 mounted upon wheels running upon a track 22 in such manner that the cylinder may be positioned 75 opposite either of the rams 17 for the purpose of forcing material through either of the chambers 42. As illustrated in Fig. 1, coacting members 19 and 20 are provided whereby the plunger of the cylinder 18 detachably engages the outer end of the ram 17.

At the discharge end of the furnace I provide a quenching basin 52 containing water 32. The quenching basin 52 is covered at its central portion by a hood 53, said hood extending outwardly from the end wall of the furnace proper and downwardly to the end wall of the quenching basin 52. The side walls 54 of the hood extend downwardly beneath the level of the water in the quenching basin 52, but not to the bottom thereof, acting as a water seal. The height of the water in the quenching basin 52 will determine the pressure existing inside of the hood and retort. An endless conveyor 30 extending around a sprocket wheel 55 and around a similar wheel, not shown, at the opposite end passes over the top of the hood 54 or otherwise and along the bottom of the quenching chamber 52. Beneath the hood 53 the floor of the quenching chamber is substantially horizontal, but outside of the hood it slopes upwardly, as shown at 56, to a level above that of the water. The coke discharged from the retort is moved upwardly 10 by the conveyor along the inclined floor 56 and discharged at 57 into a car, storage bins or other receptacle.

In some instances I may prefer to remove the coke from the quenching basin by circulating water through the basin employing a current of sufficient strength to carry the coke to the exterior of the basin.

Leading upwardly from the retort at several points along its length are discharge pipes 15 provided for the purpose of conducting the products of distillation to a system of condensers and washers or purifiers for the purpose of reclaiming separately the by-products distilled at different tempera- 12 13

tares, the residue or fuel gas being conducted to the burner 60 for the purpose of supplying heat to the retort in the manner above described.

5 In operation, coal is fed into the hopper 16 from movable cranes, continuous conveyors or other means well-known in the art, and is then forced through the chamber 42 by means of the ram 17. The burner 60 being 10 located at the discharge end, as illustrated, the maximum heat of the retort will be at the discharge end 44. As the products of combustion circulate toward the receiving end the heat will be progressively taken 15 therefrom thus causing the heat of the retort to progressively diminish from the discharge to the charging end. At the discharge end the flues 12 are, as above described, constructed of hollow tiles as thin 20 as structural considerations will permit.

About half way from the discharge to the receiving end of the furnace, or at some other intermediate point, as determined by special circumstances, the heat of the products of combustion will be decreased to such 25 a point as to permit of the substitution of cast iron flues for the hollow tiles used at the discharge end. The cast iron having superior heat conductivity serves to rapidly conduct a large part of the remaining heat of the products of combustion in the surrounding ducts to the interior of the retort, and the parts are so proportioned that a large 30 part of the effective heat is abstracted from 35 the products of combustion before they escape from the pipe 51.

The air for the support of combustion is supplied through the pipe 10 at the receiving end of the furnace and circulates back 40 and forth through the flues 13 to the discharge end. By means of this construction and operation it will be observed that neither cold coal or cold air comes in contact with the highly heated parts of the 45 furnace, but that both air and coal are supplied at the coolest parts of the furnace and are progressively heated during their progress toward the point of maximum heat at the discharge end. This mode of operating 50 ovens is conducive to the durability of the walls of the retort and insures economy in its operation.

As the coal enters the receiving end it receives heat from the flues 12 and after it has 55 progressed a short distance the gases having a low temperature of vaporization will be distilled, and as the coal progresses to the hotter parts of the retort gases having a higher temperature of vaporization will be 60 given off, and finally the material will reach the discharge end in the form of coke. The coke is discharged directly into the quenching basin 52. The discharge of the hot coke into the water in the quenching basin gives 65 rise to the formation of a large amount of

steam, which being prevented from escaping by means of the water seal formed by the hood 53, passes back into the retort, where coming in contact with incandescent coke, water gas is formed in the usual manner. 70 The water gas mixes with the ordinary products of distillation and passes off through the pipes 15. By this means an increased quantity of gas is formed thus insuring a plentiful supply for the heating of 75 the retort and other purposes. The progressive heating of the coal as it passes toward the discharge end of the retort, in connection with the use of a plurality of outlet pipes 15 renders it possible to separate to a 80 considerable extent the gases having different temperatures of volatilization and different by-products it being well known that the various by-products volatilize at different 85 temperatures.

The interior dimensions of the retort constitute one of its greatest advantages. The width of the retort, or of each chamber of a double retort is three or four times its height. Preferably, the height of each 90 chamber is about a foot and a half and the width of each chamber is four or five feet. As illustrated in the drawings, the side walls 46 of the retort chambers are comparatively 95 thick, being so constructed to support the weight of the parts above, while the walls of the flues 12 are thin as structural considerations will permit. The transmission of heat to the coal therefore is almost entirely in a vertical direction, this being the direction 100 of escape of the distilled gases. By this means the coke may be obtained in much less broken form than results from the use of vertical furnaces having a height greatly in excess of the width and in which the heat 105 is supplied at the sides.

I claim:

1. In a coking oven, a retort, flues above and below said retort and leading from end to end thereof, said flues being constructed 110 of refractory material at the discharge end of said retort and of material of relatively high heat conductivity at the receiving end, and a furnace communicating with said flues at the discharge end of said retort.

2. In a continuous coking furnace, a horizontal retort, a roof therefor of hollow tiles forming heating flues, and an external protective roof supported independently of said tile roof.

3. In a coking oven, an exterior arch, a retort, and a hollow tile roof formed of heating flues above said retort and supported independently of said exterior arch.

4. In a coking oven, a retort of greater width than height, a furnace, flues above and below said retort and communicating with said furnace, and air heating flues adjacent said first named flues.

5. In a coking oven, a retort of greater 130

width than height, means for forcing material endwise through said retort, an exterior arch above said retort, a furnace at the discharge end of said retort, hollow tile flues forming the roof of said retort and communicating with said furnace, and hollow tile air heating flues above said first named

flues, said hollow tile flues being supported independently of said exterior arch.

LELAND L. SUMMERS.
